JOHN HAYS HAMMOND, JR., OF GLOUCESTER, MASSACHUSETTS.

ORGAN.

Application filed December 12, 1922, Serial No. 606,373. Renewed March 23, 1928.

Some of the objects of the present invention are to provide improved means for playing a musical instrument automatically; to provide improved means for controlling several organs comprising a musical instrument simultaneously; to provide single means for controlling the playing of the notes of a pipe organ and for controlling the swell shutters thereof; to provide an improved form of control mechanism for controlling the swell shutters of an organ; and to provide means for modifying the action of said control mechanism.

Other objects will appear from the following description taken in connection with the accompanying drawing, in which there is shown so much of a pipe organ, embodying the invention, as is necessary to an understanding of the invention.

Referring to the accompanying drawing, one embodiment of this invention comprises player mechanism 10, two similar control mechanisms 11 and 12, each of which controls the swell engines 13 and 14 of two organs, not shown, and a pedal mechanism 15 for modifying the action of the control mechanisms 11 and 12. The player mechanism 10 consists of an air-tight box 20 provided in front with a removable plate of glass 21, a tracker bar 22 and two mechanically operated rolls 23 and 24. Mounted upon these rolls is the usual paper strip 25 provided with openings for playing the music. The tracker bar 22 is provided with two sets of holes 28 and 29 which operate the notes of the two organs in a well-known manner. Connected to the box 20 is a pipe 31 leading to a supply of air under pressure which passes into the box 20 and when an opening in the paper 25 comes opposite a hole in the tracker bar the air passes into this hole and causes the corresponding note of the organ to be sounded. Such player actions are indicated only diagrammatically in the drawing, as such note playing mechanisms are well known in the art.

The tracker bar 22 is also provided with two sets of holes 33 and 34, 35 and 36, which are connected by the pipes 37, 38, 39 and 40 to the two control mechanisms 11 and 12 respectively. The two control mechanisms 11 and 12 being identical in construction will be numbered similarly in the following description. Each mechanism consists of a circular member of insulating material 45 loosely mounted upon a shaft 46 which in

turn is loosely mounted in the brackets 47 and 48. Rigidly secured to each member 45 is a ratchet 49, a notched wheel 50 and a second ratchet 51 which has its teeth in the opposite direction to the ratchet 49. Sleeves 52 and 53 are provided which slide over the shaft 46 and hold the members 45 together with their ratchets in the proper position on the shaft 46. Co-operating with the ratchets 49 are rods 55 provided with teeth 56 which engage the teeth of the ratchets 49 and thus serve to rotate the members 45. The other ends of the rods 55 are pivoted to bellows 60 and are held in the position shown by means of springs 61. The bellows 60 are provided with small openings 62 and are connected to the pipes 38 and 40 respectively. Co-operating with the ratchets 51 are rods 65 provided with teeth 66 which at suitable times engage the teeth of the ratchets 51 and thus serve to rotate the members 45 in an opposite direction. The rods 65 are held in the positions shown by means of springs 67 and are pivoted at their far ends to bellows 68 which are provided with small holes 69 and are connected to the pipes 37 and 39 respectively. The ratchets 49 and 51 have one or more teeth removed at certain positions, the object of which appears in the description which follows:

The rods 55 and 65 are guided by slots 71 and 72 provided in member 73. Co-operating with the notched wheels 50 are spring pressed centering springs or clickers 75 which are rigidly secured to the base 76. The bellows 60 and 68 are supported by brackets 78 and 79 rigidly secured to the base 76. The members 45 are provided with segments 80 of conducting material inserted in their peripheries. Rigidly secured to the rod 46 are sectors 81 made of insulating material. Secured to these sectors are four brushes 82, 83, 84 and 85 which bear on the peripheries of the members 45, and at suitable times successively engage the sectors 80. The brushes 82 are connected by a conductor 88 to one side of a battery 90. The brushes 83, 84, and 85 of the control mechanism 11 are connected by conductors 91, 92 and 93 to terminals 94, 95 and 96 which are secured to the swell chest motor 13 and operate the mechanism therein in a well-known manner. The brushes 83, 84 and 85 of the control mechanism 12 are connected by conductors 97, 98 and 99 to terminals 100, 101 and 102 of the swell chest

motor 14. The return currents from the swell chest motors 13 and 14 pass from the terminals 104 and 105 to the conductors 106 and 107 and thence to the other side of the battery 90.

Rigidly secured to the end of the shaft 46 is an arm 110 to which is pivoted a link 111, the other end of which is pivoted to a pedal 112, this pedal being loosely mounted upon 10 a rod 113 supported by the brackets 114 and 115 from the base 76.

In the operation of this form of the invention shown in the accompanying figure, the paper strip 25 is unwound from the roll 23 and wound up upon the roll 24, thereby 15 passing over the tracker bar 22. As air under pressure passes in thru the pipe 31 from an outside source not shown, the interior of the box 10 will be under pressure. The air 20 will be prevented from passing into the holes of the tracker bar 22, as the paper strip 25 will be pressed tightly against the face of the tracker bar. As the paper strip 25 is moved across the tracker bar 22, the openings 25 in the paper pass in front of the corresponding holes in the tracker bar 22. When an opening in the paper strip 25 passes in front of any of the holes 28 or 29, air under pressure is admitted to the corresponding hole, thus sounding a corresponding note in the organ. The mechanism up to this point is of any well-known 30 standard construction and design, and need not be more fully described herein.

35 When an opening in the paper strip 25 passes in front of the hole 34, air is admitted under pressure to the pipe 38, and thence to the bellows 60 which is thereby inflated the opening 62 being so small that only a small amount of air is lost thru 40 this means. This causes the rod 55 to be moved to the left, as seen in the figure. The tooth 56 engages the teeth of the ratchet wheel 49 which is thereby rotated through the distance of one tooth and the member 45 which is rigidly secured thereto is therefore rotated through a like amount amount. The member 45 is held in this position by means of the clicker 75 acting against the 50 notched wheel 50. The ratchet 51, being rigid with the ratchet 49, is also rotated, but as the tooth 66 on the rod 65 is out of the path of the ratchet teeth, it is not engaged by them. After the opening in the paper 55 25 has passed beyond the hole 34, the supply of air is cut off from the pipe 38 and the bellows 60 is deflated under the action of the return spring 61, the air escaping through the opening 62. The tooth 56 merely slides over the teeth of the ratchet 49 without turning the same, which is held in 60 position by the clicker 75. The operation just described causes the segment of conducting material 80 to be moved under the brush 83 thus closing the circuit through

70 this brush conductor 91, terminal 94 and thence through the mechanism of the swell engine 13 to the terminal 104, then through the return conductors 107 and 106 to the battery 90, the circuit being completed from this battery to the brush 82 by means of the conductor 88. The swell engine 13 is thereby operated to open the swell shutters a small amount.

75 When another opening passes in front of the hole 34, a similar action to that just described takes place and the member 45 is rotated an additional amount sufficient to bring the contact segment 80 under brush 80 84. This closes the circuit through the terminal 95 of the swell engine 13, thus causing the swell shutters of the corresponding organ to be opened an additional amount. Thus, when a third opening passes in front 85 of the hole 34, contact strip 80 is moved under the brush 84, thus closing the circuit through the terminal 96 which causes the swell engine 13 to open the swell shutters the full amount. If another opening should 90 pass in front of the hole 34 the rod 55 would be actuated, but the tooth 56 would not engage a tooth of the ratchet 49, as several teeth in this position have been cut away so that the mechanism cannot be moved farther in that direction.

95 When an opening in the paper 25 passes in front of the hole 33, air under pressure is admitted to the pipe 37 and thence to the bellows 68 which is thereby inflated. This causes the member 65 to be moved to the left and the tooth 66 to engage one of the teeth of the ratchet 51, thus causing the member 45 to be rotated through a small angle which corresponds to the spacing of the teeth of the ratchet 51. This moves the 100 contact strip 80 so that it is no longer under the brush 85 and thereby deenergizes the circuit through the terminal 96 which causes the swell engine 13 to close the swell shutter a small amount. When the second opening passes the hole 33, the operation is 105 repeated and the circuit through the terminal 95 is deenergized thus causing the swell shutters to be closed an additional amount. A third opening passing in front of the hole 110 33 repeats this action causing the swell shutters to be entirely closed thus returning the parts of the control mechanism 11 to the position shown in the figure. If another opening should pass in front of the hole 33 the rod 65 would be actuated, but the tooth 66 would not engage a tooth of the ratchet 51, as several teeth in this position have been 115 cut away so that the mechanism cannot be moved farther in that direction.

120 It is seen from this description that the swell shutters controlled by the swell engine 13 are opened successive amounts as openings in the paper 25 pass in front of the hole 34 and are closed successive amounts when 130

openings in the paper 25 pass in front of the hole 33. In this manner the opening of the swell shutters can be controlled from two sets of openings in the paper 25, co-operating with two holes in the tracker bar 22. In the figure shown, only three positions of the swell shutters are indicated; but in actual practice this number is considerably increased.

10 The operation of the control mechanism 12 is identical to that just described for the control mechanism 11, and is controlled by openings in the paper 25 passing in front of the holes 36 and 35, and thereby controlling 15 the swell engine 14 in a manner previously described for the swell engine 13.

If it is desired to operate the swell shutters by means of a foot pedal 112, this is rotated, say, in a clockwise direction, as seen 20 in the figure, which, by means of the link 111 and arm 110, rotate the shaft 46 in a clockwise direction, which causes the two sectors 81 of the mechanisms 11 and 12 to be rotated through an equal amount thereby 25 successfully bringing the contacts 83, 84 and 85 into engagement with the contact strip 80. By rotating the pedal 112 in an opposite direction, this action can be reversed, thus closing the swell shutters successive 30 amounts.

The action of the pedal 112 can be superimposed upon the action of the two mechanisms 11 and 12 so as to modify their action as produced by the paper 25. For example, 35 if the member 45 of the mechanism 11 were in such a position as to energize the circuits controlled by brushes 83 and 84, the swell shutters controlled by the swell engine 13 would be open about two-thirds of the full 40 amount. By rotating the pedal 112 in a clockwise direction through a small amount, the swell shutters controlled by the swell engine 13 will be opened the full amount, whereas, if the pedal 112 is rotated in a 45 counter-clockwise direction, it will cause the brushes 84 and 83 to move off the segment 80, thus closing the swell shutters which are controlled by the swell engine 13. This action is controlled from the panel 112 and modifies 50 the action of the mechanisms 11 and 12.

The invention upon which this application is based is broader than the specific embodiments shown and described for the purposes of illustrating some of the ways in 55 which it may be employed. The scope of the invention is therefore understood not to be limited by the present specific description. I intend no limitations other than those imposed by the appended claims.

60 What I claim is:

1. In a musical instrument, the combination with automatic means for producing musical sound, and a swell motor for varying the intensity of sound emitted from the

instrument, of control mechanism controlled 65 by the automatic means to actuate said swell motor, said control mechanism including a rotatable shaft, a pair of ratchet wheels loosely mounted thereon, a rotary selector element loosely mounted on the shaft and 70 operatively connected to said ratchet wheels, contacting elements cooperating with said selector elements and included in the circuit of the swell motor, a pawl for each of the ratchets, and a bellows for actuating each 75 pawl.

2. In a musical instrument, the combination with automatic means for producing musical sound, a swell motor for varying the intensity of sound emitted from the instrument, automatic control mechanism controlled by the automatic player mechanism to actuate said swell motor, said automatic control mechanism including a rotatable shaft, a pair of ratchet wheels loosely mounted 80 thereon, a rotary selector element loosely mounted on the shaft and operatively connected to said ratchet wheels, contacting elements cooperating with said selector 85 elements and included in the circuit of the swell motor, a pawl for each of the ratchets and bellows for actuating each pawl, and additional control mechanism movable at the will of an operator for modifying the 90 relative action of said contracting elements and rotary selector. 95

3. In a musical instrument, the combination with automatic means for producing musical sound, a swell motor for varying the intensity of sound emitted from the instrument, automatic control mechanism controlled by the automatic player mechanism to actuate said swell motor, said automatic control mechanism including a rotatable shaft, a pair of ratchet wheels 100 loosely mounted thereon, a rotary selector element loosely mounted on the shaft and operatively connected to said ratchet wheels, contacting elements mounted on said shaft and movable therewith to cooperate with 105 said selecting element and included in the circuit of the swell motor, a pawl for each of the ratchets and bellows for actuating each pawl, and additional control mechanism movable at the will of an operator for rotating said shaft. 110

4. In a musical instrument, automatic means for producing sound, a swell motor for varying the intensity of sound emitted, and control mechanism controlled by the 120 automatic player mechanism, said control mechanism comprising a rotary selecting device for controlling the action of the swell motor and having a pneumatic bellows for rotating the selecting device step by step in one direction and a second bellows for rotating the selecting device step by step in the opposite direction, and elec- 125

trical contacts in circuit with the swell motor controlled by the selecting device.

5. In a musical instrument, the combination with a plurality of organ actions for producing musical sound, an automatic player mechanism for operating said actions, and a swell motor for each of said actions to vary the intensity of sound emitted from the respective action, of control mechanism including a rotatable shaft, a plurality of rotary selectors loosely mounted on the shaft for controlling said organ actions respectively, progressively acting pneumatic means for operating said selector elements, respec-

tively, and controlled by said automatic means, a plurality of contacting elements cooperating with each selector element and included in the circuit of the respective swell motor, said contacting elements being mounted on said shaft and movable therewith, and a pedal operatively connected to the shaft for actuating all of said contacting elements independently of the respective selector elements.

10 In testimony whereof I hereunto affix my signature.

JOHN HAYS HAMMOND, JR.
